FIG. 5

UNITED STATES PATENT AND TRADEMARK OFFICE
CERTIFICATE OF CORRECTION

PATENT NO. : Des. 357,573

DATED : April 25, 1995

INVENTOR(S) : Patricia D. Ng

It is certified that error appears in the above-identified patent and that said Letters Patent is hereby corrected as shown below:

Column 1, under "References Cited, U.S. Patent Documents" delete "D. 311,829" and substitute -- D. 331,829--therefor.

Signed and Sealed this

Twentieth Day of June, 1995

Attest:

Attesting Officer

BRUCE LEHMAN

Commissioner of Patents and Trademarks
